UNITED STATES PATENT OFFICE.

GEORGE E. FRAZIER, OF CLEVER, MISSOURI, ASSIGNOR OF ONE-HALF TO SCHYLER C. COBB, OF CLEVER, MISSOURI.

AUTOMATIC TATTING APPARATUS.

1,350,445.

Specification of Letters Patent. Patented Aug. 24, 1920.

Application filed March 13, 1920. Serial No. 365,623.

To all whom it may concern:

Be it known that I, GEORGE E. FRAZIER, a citizen of the United States, residing at Clever, in the county of Christian and 5 State of Missouri, have invented certain new and useful Improvements in Automatic Tatting Apparatus, of which the following is a specification, reference being had to the accompanying drawings.

10 This invention relates to a tatting apparatus and method of tatting and has for its object to provide an apparatus of this character which works very rapidly and accurately.

15 Another object is to provide an apparatus of this character which is capable of working any design.

Another object of the invention is to provide an apparatus of this character so arranged that the only operation the hands of 20 the user performs is that of holding the completed work and applying the thread to the apparatus.

A still further object of the invention is to 25 provide an apparatus of this character, the greater portion of which can be stamped from sheet metal.

Another object is to provide a method of 30 tatting which is simple, rapid, accurate, and whereby a complicated design may be worked with rapidity by an inexperienced person.

With these and other objects in view the invention consists in the improved construction and arrangement of parts to be herein-after more particularly described, fully claimed and illustrated in the accompanying drawings, in which:

Figure 1 is a perspective view of a tatting apparatus constructed in accordance with 40 an embodiment of my invention, and showing the position of the thread before being placed on to the bobbin,

Fig. 2 is a side elevation and sectional view,

Fig. 3 is a section taken on the line 3—3 of Fig. 2,

Fig. 4 is a section taken on the line 4—4 of Fig. 2.

50 Referring to the drawings, 5 designates the apparatus, the main portion of which consists of a single length of material having its end portion 6 bowed to provide a handle. The intermediate portion of the 55 length includes a pair of oppositely extend-

ing ears 7, which are extended upwardly in right angular relation to the length. The end portion 8 of the length is enlarged, the enlarged portions being extended toward each other and terminating in spaced relation to provide a bobbin holder 9. The length of material is bent adjacent the ears 7 so that the bobbin holder 9 extends substantially parallel to the handle 6. Projecting from the end 9' of the length is a lug 10, which is extended in angular relation to the length to serve as a support.

The extremity of the handle 6 is curled upon itself to provide a bearing 11 in which the intermediate portion of a length of wire 12 is disposed, the end portion of the wire being extended upwardly and passed through the ears 7. This wire, not only permits the handle to be adjusted to accommodate the hand of the user but its ends also 75 perform an additional function to be hereinafter described. A loop forming and guide member 13 is provided, and consists of a length of material including ears 14 adjacent its end 15. The ears 14, are pivotally 80 mounted on the ends of the wire 12, between the ears 7. In view of this the end 16 of the guide member 13 is overbalanced so that it will engage the upper portion of the handle 6 and hold the guide member 13 normally 85 in a horizontal position, the end 15 of said member projecting over one end of the bobbin holder 9. It will be noted that the upper end 17 of the bobbin holder is cut away, the apparatus inclining from the ears 90 7 to the bobbin holder. A bobbin 18 having transversely concaved sides, and an endless deep groove is disposed between said sides and ends. The bobbin 18 is intended 95 to be disposed within the bobbin holder in spaced relation thereto, to permit the passage of a thread between the bobbin and the bobbin holder. The bobbin is supported by the lug 10 and has its ends projecting beyond the ends of the bobbin holder.

100 The operation of this novel apparatus, is very simple. It consists of winding thread on the bobbin 18, placing the bobbin in the bobbin holder with one end of the thread projecting downwardly. The second, third and fourth fingers of the left hand of the user are passed through the handle portion formed by the portion 6 and wire 12. A thread from an independent spool or source 105 19 has its end held together with the end of 110

the thread of the bobbin by means of the first and fifth fingers of the left hand. A strand of thread from the spool 19 is then passed over the end 15 of the member 13 so as to form a loop. The user then exerts pressure on the end 15 by means of the thread causing the end 15 to swing downwardly into engagement with the end of the bobbin 18. By continuing the movement of the thread downwardly the loop is caused to pass over the bobbin between the bobbin and the bobbin holder with a portion of the thread passing through the slot formed in the bobbin holder, and then on to the thread of the bobbin. The direction of application of thread to the loop forming and guide member 13 may alternate to produce the design desired.

This apparatus eliminates the tiresome method of constantly moving the wrist, which is necessary in the old method of tatting. All the operator has to do with this apparatus is to hold the ends of the threads and supply the thread to loop the forming and guide member. The apparatus does the rest and performs the work accurately regardless of the rapidity with which it may be operated. Notwithstanding these important features the apparatus is capable of being formed from a small quantity of sheet metal.

From the foregoing it will be readily seen that this invention revolutionizes tatting to render the same more simple so that an inexperienced person may produce a complicated design with speed and accuracy. The apparatus itself not only renders the work more pleasant, but simplifies the method of tatting and as the bobbin holder and bobbin are stationary with respect to the handle portion and hand of the user supporting the apparatus, the possibility of a mistake in the design of the work is eliminated. Furthermore, as previously stated all the user has to do is to hold the bobbin holder and the ends of the threads, and supply thread to the loop forming member.

What is claimed is:—

1. As an article of manufacture, an apparatus of the character described comprising a bobbin holder having a slot in one of its walls and means at one end for supporting a bobbin, the walls of said holder loosely embracing the bobbin, whereby a loop of thread may be passed over the bobbin through the holder and drawn from beneath the bobbin and beyond the holder.

2. An apparatus of the character described comprising a bobbin holder, a bobbin carried by the holder, and a loop forming guide member carried by said holder, said member being movable into and out of engagement with the bobbin.

3. An apparatus of the character described comprising a bobbin holder, a thread

carrying bobbin carried by the holder, and loop forming guide means carried by the holder, whereby a loop may be formed on said loop forming guide means from a supply of thread independently of the thread of the bobbin and may be guided on to the bobbin, said bobbin acting to guide the loop of thread on to the thread from the bobbin to encircle the same.

4. In apparatus of the character described comprising a bobbin holder, a thread carrying ribbon therein, and loop guiding means carried by the holder and coöperating with the bobbin to guide a loop of thread on and around one end of the bobbin, said bobbin acting to guide the loop of thread through the holder on to and around the thread from the bobbin.

5. An apparatus of the character described comprising a bobbin holder, a thread carrying bobbin therein, and loop guiding means carried by the holder, said means being larger than the bobbin and movable to embrace the bobbin to guide a loop of thread on to the bobbin.

6. An apparatus of the character described comprising a handle, a bobbin holder on one end of said handle, a bobbin freely disposed in said holder and movable means carried by the handle and disposed at the junction of the bobbin holder with the handle for guiding a loop of thread on to the adjacent end of the bobbin.

7. An apparatus of the character described comprising a handle member, a bobbin holder on one end of said handle, said handle having a slot, a bobbin freely disposed in said holder and movable loop forming and guide means mounted on said handle and disposed at the junction of the bobbin holder with the handle whereby a supply of looped thread is guided on to the adjacent end of the bobbin, and manually drawn over the bobbin through the slot on to the thread of the bobbin.

8. An apparatus of the character described comprising a bobbin holder, means for supporting said holder, a bobbin freely disposed in the holder, and a loop forming and guide member pivoted to said bobbin holder above the bobbin, one end of said member being heavier than the other, said end being adapted to receive a supply of thread, and movable into engagement with the bobbin over one end of said bobbin, and disengaged through the medium of the weight of the heavier end from said end of the bobbin.

9. An apparatus of the character described comprising a handle, a bobbin holder formed on one end portion of said handle, a lug projecting from the end of the bobbin holder, a bobbin disposed in said bobbin holder and supported by the lug, a thread loop forming guide member pivoted

to one side of its center to the handle portion in angular relation to the bobbin, said loop forming guide member being movable to guide a supply of looped thread on to 5 the bobbin.

10. An apparatus of the character described comprising a handle portion, a bobbin holder on one end portion of the handle portion, ears projecting from the handle portion between said handle portion and the holder, a second handle portion connected to the other end of the first mentioned handle portion and having its end extending through the ears, a thread loop forming 15 and guide member pivoted on the ends of the second mentioned handle portion between said ears, and a bobbin disposed in said holder, said loop forming and guide member being manually movable through 20 the medium of a supply of thread into engagement with the bobbin and movable to its normal position by gravity.

11. An apparatus of the character described comprising a single length of material bent upon itself with its end portions substantially in parallel relation to each other, oppositely extending wings projecting over one of the said end portions, said wings being bent upon said end portion toward and 25 terminating in spaced relation to each other to provide a bobbin holder, a lug projecting 30

from said end adjacent the bobbin holder, ears projecting in right angular relation to said handle and in spaced relation to each other, a semi-cylindrical thread loop forming 35 and guide member including ears adjacent one end portion, the ears of said member being pivoted to the first mentioned ears, and a bobbin disposed in the holder, said bobbin being supported by the lug. 40

12. As an article of manufacture, an apparatus of the character described comprising a bobbin holder adapted to loosely embrace and support a bobbin therein, a portion of the walls of the holder adjacent one 45 end being extended beyond and away from the holder to form a guide wall, whereby a loop of thread may be passed on to the bobbin within the holder and drawn from beneath the bobbin beyond the same. 50

13. As an article of manufacture, an apparatus of the character described comprising a bobbin holder adapted to loosely embrace and support a bobbin therein, a portion of the walls of the holder adjacent one 55 end being extended beyond and away from the holder to form a guide wall, and a loop forming guide member carried by said holder adjacent said guide wall.

In testimony whereof I hereunto affix my 60 signature.

GEORGE E. FRAZIER.
